CLAIM

The ornamental design for a hand mixer housing, as shown and described.

DESCRIPTION

FIG. 1 is a top front and right side perspective view of a hand mixer housing, showing my new design; FIG. 2 is a right side elevational view thereof, the fragmentary broken lines indicating the shank of a beater are shown for illustrative purposes only;

FIG. 3 is a left side elevational view thereof;

FIG. 4 is a top plan view thereof;

FIG. 5 is a bottom plan view thereof;

FIG. 6 is a front end elevational view thereof; and

FIG. 7 is a rear end elevational view thereof.
